PLAYGROUND CLIMBER OR SIMILAR DEVICE

Robert S. Wormser, Hillsdale, Mich., assignor to Game Time, Inc., Litchfield, Mich., a corporation of Michigan

Filed Nov. 26, 1968, Ser. No. 14,683

Term of patent 14 years

Int. Cl. D21—03

U.S. Cl. D34—5

FIG. 1

FIG. 2

FIG. 3

FIG. 4

FIG. 1 is a side, elevational view of my new design representing a playground climber or similar device in the form of a fish,

FIG. 2 is a front view as taken from the left of FIG. 1,

FIG. 3 is a rear view of the playground climber or similar device of the invention as taken from the right of FIG. 1, and

FIG. 4 is a top, plan view.

The characteristic features of my design reside in the nose-like front projection, the "eye" representation and the fish-tail rear projection, all of which, when combined with a conical framework, suggest a fish.

I claim:

The ornamental design for a playground climber or similar device, substantially as shown.
